UNITED STATES PATENT OFFICE.

MICHAEL J. KANE, OF BUFFALO, NEW YORK.

DESIGN FOR A BADGE.

SPECIFICATION forming part of Design No. 35,986, dated August 5, 1902.

Application filed May 6, 1902. Serial No. 106,232. Term of patent 3½ years.

To all whom it may concern:

Be it known that I, MICHAEL J. KANE, a citizen of the United States, residing at Buffalo, in the county of Erie and State of New York, have invented a new, original, and ornamental Design for a Badge, of which the following is a specification, reference being had to the annexed drawing, forming part thereof.

The figure in the drawing represents a front view of my new design.

As shown in the drawing, the leading or material features of my design consist of a Maltese cross A, with a helmet in a circular space B in the middle of the cross and a ring D, concentric with said circular space, placed between it and the outer ends of the arms, crossing alternately over and under said arms,

with two swords a a placed in the openings between the arms of the cross in front of the ring D and crossing under the circular space 20 and helmet in the center.

Having described my invention, what I claim as new, and desire to secure by Letters Patent, is—

The ornamental design for a badge as herein shown and described.

In testimony whereof I have signed my name to this specification in the presence of two subscribing witnesses.

MICHAEL J. KANE.
